(57) **CLAIM**

The ornamental design for an alcohol beverage bottle, as shown and described.

DESCRIPTION

FIG. 1 is a top perspective view of a first embodiment of an alcohol beverage bottle showing the claimed design; FIG. 2 is a front elevational view of the embodiment of FIG. 1;

FIG. 3 is a top plan view of the embodiment of FIG. 1; FIG. 4 is a bottom plan view of the embodiment of FIG. 1; FIG. 5 is a top perspective view of a second embodiment of the alcohol beverage bottle, showing the claimed design; FIG. 6 is a front elevational view of the embodiment of FIG. 5;

FIG. 7 is a top plan view of the embodiment of FIG. 5; and, FIG. 8 is a bottom plan view of the embodiment of FIG. 5. The broken lines shown throughout depict unclaimed portions of the alcohol beverage bottle and form no part of the claimed design.

1 Claim, 6 Drawing Sheets
